ROTATING CUTTING DEVICE

Giacomo Coretti, Dalmine, Italy, assignor to
Dalmine S. A., Dalmine, ItalyApplication June 18, 1947, Serial No. 755,290
In Italy July 30, 1946

6 Claims. (Cl. 164—60)

1

This invention relates to a cutter-block with cam-operated concentric feed of revolving knives, controlled through a clutch, by one or more pairs of differential gears, particularly for pipe cutters.

Conventional cutter-blocks with revolving knives, which are at present employed on pipe cutting machines, show a very intricate design, causing therefore high maintenance costs. So, for instance for the feed and back strokes of knives, extremely complicated operating devices are required, involving a large number of wear exposed gearings. In addition, such cutter blocks are always very heavy and bulky, and a replacement of a great part of the gears, and above all of the guides, is indispensable in frequent intervals.

This invention relates to a special cutter block with revolving knives, by which abovesaid inconveniences are wholly prevented, and which shows a less complicated design comparing with those employed at present, requiring therefore less maintenance costs, while securing perfect results.

In principle, the invention consists in a hollow cylindrical member, on which a fixed gear is fitted, being the other mating gear—coupled to the first one through one or more pairs of differential gears—fitted loose on a second cylindrical member, revolving on the first hollow member, and which is called, by reason of its function "cam holder." A ring, located between said two toothed wheels, is pressed by means of springs against the fixed gear; ring and gear are adapted to engage by means of a small number of projections and recesses, while same ring, after accomplishing a movement sufficient to disengage it from the recesses, gets engaged with the loose gear by means of dogs, friction clutches or of any mechanical or magneto-electric system allowing a practically instantaneous coupling of the various members. To this end, on the "cam holder," a plate showing an inside multiple profile track or slot is fitted. Against such profile tracks (or inside of the slot) rest the rollers of the tool holder slides, with or without return springs, which slides are at the same time moving on guides connected to the hollow cylindrical member.

Through the application of such a system, the following advantages are attained:

(1) A reduction of the cutter block weight down to less than two-thirds of that of the conventional types.

(2) A reduction of stresses, and consequently of the wear of tool holder slides, since the force

2

is now applied at the center, instead on the ends, as in conventional types.

(3) Avoiding a self-penetration of the tool on the material which is to be cut, thanks to the action of the springs, and of the profile slot, by which the rollers are forced against the track, whereby the possibility of tool breakages is almost completely excluded.

(4) Obtaining a remarkable saving in power consumption, owing to the reduction of frictional resistances (in the practice, while cutting with this new apparatus, an input of 2.5-3 amp. is required, in comparison of 6-7 amp. required in the use of heads of the conventional types).

(5) Complete lubrication of all moving parts from the outside, contrary to the old types.

(6) Adjustment of one tool independent from all others, while on old types it is necessary to adjust tools in pairs, making more difficult such an operation, and requiring also a longer time.

For a better understanding of this invention, a merely exemplifying and not binding embodiment form is shown in the accompanying drawing.

25 In same drawing:

Fig. 1 shows a side-view of the partially sectioned device.

Fig. 2 shows a front view of a detail (multiple cam with inside track).

30 To the spindle A of the apparatus is fixed the toothed driving wheel B of the differential gears. To the hub B₁ of the wheel is rigidly secured the annular member B₂, while the slide carrying disc N is keyed to annular member B₂ by key K. These parts revolve, therefore, with the velocity of the spindle of the apparatus. Loose on the hub B₁ is fitted the cam carrying member F furnished with the hub F₁ on which revolves loosely the toothed drive wheel E. The

35 toothed wheel B engages the gear O₁, consisting of two toothed wheels O₁, and O₂ of slightly different diameter, which are keyed to a hollow shaft O₃ rotating on a fixed axle O₄. Consequently, the toothed wheel E, engaging the gear O₂, revolves on the basis of the chosen gear ratio in the same direction and with a slightly slower speed compared to that of the wheel B.

40 On the same hub F₁ is fitted a collar D which can be displaced axially by means of a foot lever or the like. The collar D is coupled to the hub F₁ by means of the key F₂ and has on one side four front cogs D₁ spaced by 90° and designed to engage in corresponding recesses C₁ of the disc

45 C, which is fixed on the gear B. On the opposite side, the collar D has a frontal gear D₃ which

3

may be saw-toothed for acting together with a corresponding frontal gear E_1 of the loose gear E .

In this manner, when (as shown in Figure 1) the collar D is displaced to the left and its cogs D_1 are lodged in the recesses C_1 , a direct coupling between the wheel B and the collar D is obtained, and similarly, between the spindle and the cam carrying member F . Under these circumstances, as the slides I holding the tools L can slide radially, but revolve with the same speed of the spindle, there is no relative motion between the rollers H whose pin is fixed to the slides I and the cam G fixed to the disc F , and therefore, no radial displacement of the tools is accomplished.

When, however, the collar D is displaced to the right, the cogs D_1 are disengaged from the disc C and coupling between the collar D and the wheel E is obtained by means of the front gears D_3 and E_1 . Thus, through the key F_2 of the collar D , the wheel E causes the cam carrying member F to revolve with a lower velocity than that of the spindle, and consequently lower also than that of the tool carrier member. The relative movement of the cam tracks along the rollers on pins H displaces the prismatic pin blocks radially. Since the tool holder I is firmly connected with the prismatic pin blocks sliding in slots of the annular member B_2 , the tools move toward the center in a cutting position as long as the cam tracks move in the direction of the arrow in Figure 2. When, however, the cam track has been turned by 90° , the roller of each pin block will snap into a recess of the cam track under the action of springs M , and the tools will be withdrawn.

The displacement to the right of the collar D is accomplished in opposition to the counter-acting springs R pressing the little pins R_1 against the gear E . The radial motion of the tool holder slides I towards the axis is executed in opposition to the springs M lodged in radial holes of the annular member B_2 , said springs pressing on the pin H_1 of the rollers H acting together with the cam G .

During the necessary rest stage for replacing the cut pipe, the collar D finds itself spaced with the four cogs D_1 in the recesses C_1 of the ring C , and consequently the cams revolve with the same velocity of the slide carrying disc and no feed of the tools is accomplished. When the collar is pressed to the right, compressing the springs R , the cam G revolves with the velocity of the gear E , and therefore, after a certain number of revolutions, the cogs D_1 will no longer be opposite the recesses C_1 , the collar D not being capable of being displaced to the left under the action of the springs R .

When, in the relative motion between gear B and gear E , these gears will have been displaced relatively by a fourth of a revolution, the cogs D_1 again find themselves opposite the recesses of the disc C , and consequently the collar D is displaced automatically to the left by means of the spring C , interrupting the connection between the wheel E and the cam carrying disc F .

The design of the kinematic members of the device is such that the disengagement of the feed members of the tool is accomplished a few moments later when—as a consequence of the particular shape of the cams G and by means of the springs M —the tools themselves and also the slides I have reverted to the position which is farthest from the axis of revolution.

I claim:

4

1. In a cutting tool, in combination, a driven shaft; a driving wheel unit rigidly secured to the said shaft; a carrier member rigidly secured to said shaft; slides radially movable on said carrier member; cutting means supported by said slides for engagement and disengagement of the work upon said radial movement of said slides; a cam disc unit rotatable on said shaft intermediately of said driving wheel and carrier member; a plurality of eccentrically directed cam tracks associated with said cam disc unit and arranged circumferentially; engagement means formed on said slides and being movable in said cam tracks so as to impart radial motion to said cutting means; recesses provided in said driving wheel unit; a toothed wheel loosely rotatable on said shaft; differential gear means adapted to drive said toothed wheel at a rotative speed different from the rotative speed of said shaft; a connecting member; axially movable on, and rotatable with said cam disc unit, and disposed intermediately of said driving wheel unit and said toothed wheel; projections provided on one axial end of said connecting member for being engaged in said recesses; disengageable means for coupling said connecting member at its other axial end with said toothed wheel and to transmit differential motion of said toothed wheel to said cam disc unit; and means for imparting axial movement to said connecting member so as to engage and disengage the said projections and recesses and so as to bring said coupling means into engagement and disengagement whereby a movement is imposed on said cam disc unit relatively to said carrier member and whereby the said cutters are moved in a radial direction.
2. In a cutting tool, in combination, a driven shaft; a driving wheel unit rigidly secured to said shaft; a carrier member rigidly secured to said shaft; slides radially movable on said carrier member; cutting means supported by said slides for engagement and disengagement of the work upon said radial movement of said slides; a cam disc unit rotatable on said shaft intermediately of said driving wheel and carrier member; a plurality of eccentrically directed cam tracks associated with said cam disc unit and arranged circumferentially; engagement means formed on said slides and being movable in said cam tracks so as to impart radial motion to said cutting means; recesses provided in said driving wheel unit; a toothed wheel loosely rotatable on said shaft; differential gear means adapted to drive said toothed wheel at a rotative speed different from the rotative speed of said shaft; a connecting member axially movable on, and rotatable with said disc unit, and disposed intermediately of said driving wheel unit and said toothed wheel; projections provided on one axial end of said connecting member for being engaged in said recesses; disengageable means for coupling said connecting member at its other axial end with said toothed wheel and to transmit differential motion of said toothed wheel to said cam disc unit; means for imparting axial movement to said connecting member so as to engage and disengage the said projections and recesses and so as to bring said coupling means into engagement and disengagement whereby a movement is imposed on said cam disc unit relatively to said carrier member and whereby the said cutters are moved in a radial direction; and resilient means for urging said slides in one radial direction.

3. In a cutting tool, in combination, a driven shaft; a driving wheel unit rigidly secured to said shaft; a carrier member rigidly secured to said shaft; slides radially movable on said carrier member; cutting means supported by said slides for engagement and disengagement of the work upon said radial movement of said slides; a cam disc unit rotatable on said shaft intermediately of said driving wheel and carrier member; a plurality of eccentrically directed cam tracks associated with said cam disc unit and arranged circumferentially; engagement means formed on said slides and being movable in said cam tracks so as to impart radial motion to said cutting means; recesses provided in said driving wheel unit; a toothed wheel loosely rotatable on said shaft; differential gear means adapted to drive said toothed wheel at a rotative speed different from the rotative speed of said shaft; a connecting member axially movable on, and rotatable with said cam disc unit, and disposed intermediately of said driving wheel unit and said toothed wheel; projections provided on one axial end of said connecting member for being engaged in said recesses; disengageable means for coupling said connecting member at its other axial end with said toothed wheel and to transmit differential motion of said toothed wheel to said cam disc unit; means for imparting axial movement to said connecting member so as to engage and disengage the said projections and recesses and so as to bring said coupling means into engagement and disengagement whereby a movement is imposed on said cam disc unit relatively to said carrier member and whereby the said cutters are moved in a radial direction; and resilient means for urging said slides in one radial direction; and resilient means for urging said connecting member in one axial direction so as to bring said projections and recesses into relative engagement.

4. In a cutting tool, in combination, a driven shaft; a driving wheel unit rigidly secured to said shaft; a carrier member rigidly secured to said shaft; slides radially movable on said carrier member; cutting means supported by said slides for engagement and disengagement of the work upon said radial movement of said slides; a cam disc unit rotatable on said shaft intermediately of said driving wheel and carrier member; a plurality of eccentrically directed cam tracks associated with said cam disc unit and arranged circumferentially; engagement means formed on said slides and being movable in said cam tracks so as to impart radial motion to said cutting means; recesses provided in said driving wheel unit; a toothed wheel loosely rotatable on said shaft; differential gear means adapted to drive said toothed wheel at a rotative speed different from the rotative speed of said shaft; a connecting member axially movable on, and rotatable with said cam disc unit, and disposed intermediately of said driving wheel unit and said toothed wheel; projections provided on one axial end of said connecting member for being engaged in said recesses; disengageable means for coupling said connecting member at its other

axial end with said toothed wheel and to transmit differential motion of said toothed wheel to said cam disc unit; means for imparting axial movement to said connecting member so as to engage and disengage the said projections and recesses and so as to bring said coupling means into engagement and disengagement whereby a movement is imposed on said cam disc unit relatively to said carrier member and whereby the said cutters are moved in a radial direction; and resilient means for urging said slides in one radial direction; and resilient means for urging said connecting member in one axial direction so as to bring said projections and recesses into relative engagement.

5. A cutting tool constructed in accordance with claim 1, wherein the said recesses and projections are circumferentially spaced by 90 degrees.

6. In a cutting tool in combination, a driven shaft; a driving wheel unit rigidly secured to said shaft; a carrier member rigidly secured to said shaft; slides radially movable on said carrier member; cutting means supported by said slides for engagement and disengagement of the work upon said radial movement of said slides; a cam disc unit rotatable on said shaft intermediately of said driving wheel and carrier member; a plurality of eccentrically directed cam tracks associated with said cam disc unit and arranged circumferentially; engagement means formed on said slides and being movable in said cam tracks so as to impart radial motion to said cutting means; a rotatable member mounted turnably about an axis coinciding with the axis of said shaft; differential driving means driven by said driving wheel unit and driving said rotatable member at a speed differing slightly from the speed of said driving wheel unit; and clutch means mounted on said cam disc unit for operatively connecting the same either with said driving wheel unit or with said rotatable member, causing said cam disc either to rotate at the same speed as said driving wheel unit or at a slightly different speed which in turn causes said cam disc unit to be displaced relative to said carrier member whereby said cam tracks cause said cutting means to move in radial direction.
